UNITED STATES PATENT OFFICE.

THEODORE H. WITTLIFF, OF CLEVELAND, OHIO.

FURNITURE CONSTRUCTION.

Application filed October 25, 1924. Serial No. 745,757.

This invention relates to furniture construction, and especially to a means for holding the several frame members of an article of furniture in rigid relation to each other. The construction may be used in substitution for the usual glue and corner block fastening methods at present used or may be supplemental thereto. More particularly it comprises a construction wherein is included an equalizing plate or bracing device adapted to apply inward tension upon the corner posts of an article of furniture in a horizontal plane approximately midway of the side frame members thereof, with the tension adjusting mechanism located in a plane other than that first referred to.

It is well known that various articles of furniture, particularly chairs, develop lost motion where the seat portion is connected with the legs, which gives such articles the appearance of insecurity after a comparatively short period of use. With chairs having cane or leather seats it is possible to apply a transverse tensioning or bracing means directly in a horizontal plane centrally of the seat supporting side members so that the tension upon the leg members will be normal to the ends of said side members. This form of furniture brace is covered in my co-pending application, Serial No. 285,429, filed March 3, 1924. Such form of brace, however, is not adapted for use with upholstered furniture wherein a series of coil springs serve to support a padded top, inasmuch as the installation of the brace would interfere with the spring action if it were possible to insert said brace at the usual place.

The principal object of the present invention is to provide a brace which may be used in a variety of places, for example, beneath the seat of an upholstered chair, in a bedstead provided with a box spring or under a table equipped with drawers, and which will apply tension to the corner posts of said article of furniture in substantially as effective a manner as a brace located in a horizontal plane centrally of the main side frame members, and at the same time will not interfere with the positioning of the spring supports for the padded seat of a chair or the standard structure of box spring for use upon a bedstead, or the free use of the drawers of the table. Other objects of the invention will appear in the course of the following description. To the

accomplishment of the foregoing and related ends, said invention, then consists of the means hereinafter fully described and particularly pointed out in the claims. 60

The annexed drawings and the following description set forth in detail certain mechanism embodying the invention, such disclosed means constituting, however, but several of various mechanical forms in which 65 the principle of the invention may be used.

In said annexed drawings:—

Fig. 1 is a bottom plan view of a chair constructed in accordance with the invention; Fig. 2 is a perspective view of one of 70 the corner tensioning devices of the preferred form; Fig. 3 is a detail top plan view partially in section showing the manner in which a corner plate of the type shown in Fig. 2 is engaged with a diagonally positioned corner bolt; Fig. 4 is a perspective view of a corner plate of a modified form of construction; Fig. 5 is a transverse sectional view showing a modified form of attaching means and corner bracing device; Fig. 6 is 75 an enlarged perspective view showing an angle plate adapted to be secured to the inner corner of an article of furniture; Fig. 7 is an enlarged perspective view showing the 80 brace portion of the corner bracing device; Fig. 8 is an enlarged perspective view showing the top portion of the corner bracing device. 85

As is clearly shown in Figs. 1 to 3 of the drawings, the preferred form of construction comprises the corner and side frame members 1, 2, of an article of furniture held together by means of a brace having a central tensioning device preferably comprising a turn-buckle 3, having flexible members 4, engaged at their central portions over friction slides 5, and having their terminal portions 6 secured to bracing devices 7 connected with the corners of the article of furniture. 90

The corner braces of the preferred form, shown in Figs. 2, 3, of the drawing, are preferably formed of sheet metal plates having a body portion 8 of substantially rectangular shape with their lower ends 9 105 turned at right angles thereto. The lower ends may be of substantially triangular outline, with a bayonet slot 11 formed therein to receive the terminal portions 6 of the flexible members of the tensioning device. 110 The upper portion of the plate is provided with a V-shaped notch 12, the lower end of

which may be provided with a slotted extension 13 of inverted T-shape. The ends 14 of the plate at each side of the V-shaped notch are preferably bent rearwardly at an angle to the body portion, and the extreme ends 15 thereof are bent into parallelism with the body portion of the plate.

The slot 13, or an equivalent construction, such as an elongated central aperture 16 10 formed in the plate of the modified form shown in Fig. 4, is adapted to receive the end of a bolt secured to the corner post of the structure. In the construction shown in Figs. 1 and 3 the corner bolt 17 is secured 15 diagonally through the corner post 1 in a horizontal plane centrally of the main side frame members 2. The corner bolt may have a head 18 suitably formed to merge with the outer face of the corner post and 20 at its inner end is screw-threaded to receive a nut 19. The modified form of corner plate shown in Fig. 4 is provided with widespread bearing arms 20 at its upper portion.

When the construction is applied to a 25 chair, the usual corner blocks are dispensed with and the corner plates 7 are positioned across each of the corners of said chair with the slot 13 or central hole 16 engaged over the corner bolt.

30 In order to prevent slipping and provide for a firm seating of the side members 2 against the corner posts 1, small angular seats or notches 21 are cut into the inner faces of the side members at the points where 35 the ends 15 of the plate contact therewith. The sides 22 of the body portion of the plate are preferably tapered downwardly so that when the plate is seated against the corner structure of a piece of furniture, before the 40 tension is applied by means of the turn-buckle, the body portion thereof will be inclined outwardly from the vertical at its lower end. The plates are seated in the corners by placing the upper ends 15 of a plate 45 in the notches 21, and engaging the slot 13 over the bolt with the inner face of the plate bearing against the washer 23 and nut 19 screwing the nuts firmly upon the bolt shanks. When thus positioned the terminal 50 portions of the tensioning device are engaged into the bayonet slots in the angular portions of said respective plates and tension is applied to the turn-buckle until the desired degree of rigidity is obtained.

55 It will be noted that the nut and washer serve as a fulcrum and draw inwardly upon the corner bolt 17 and the corner posts 1, and that through the lever action of the plate, pressure is applied by the terminals 15 60 against the notches of the side members, forcing the same outwardly. Thus, the side members and the respective posts are drawn into firm contact and extreme rigidity of the article of furniture is obtained. In fact, so 65 strong a structure is provided that the use of

glue, or other fastening means, between the several structural members of said article of furniture may be dispensed with, and the tensioning device and its associated parts may constitute the sole means for holding 70 the same together.

A modified form of bolt connection and corner bracing device is disclosed in Figs. 5 to 8, inclusive. It is to be understood that the bolt connection may be used with either 75 of the forms of corner plates shown in Figs. 2 and 4, and that the corner bracing device may be used with a bolt passing through the corner post of the type illustrated in Fig. 3. Likewise the angle plate, shown particularly 80 in Fig. 6, is adapted for use with an eye bolt, of the character disclosed in Fig. 5, or may serve as a point of attachment for one of the terminals of the cable connections of a tensioning device of the usual character 85 when the same is not to be offset below a central horizontal plane through the intermediate portions of the side frame members of an article of furniture.

The angle plate preferably comprises an 90 elongated strip of sheet metal 21 bent to cylindrical form adjacent its intermediate portion 22 and thence outwardly on each side to provide short intermediate sections 23 at right angles to each other and then bent reversely to said intermediate sections and at right angles thereto so as to provide fastening flanges 24 through which a plurality of screw holes 25 are formed. A transverse slot 26 is formed across the cylindrical and intermediate portions of the angle plate and is adapted to receive therein the eye of a corner bolt 27 of the character shown in Fig. 5 or the loop or chain link of a tensioning cable terminal when said device is to be attached directly to said plate. When the fastening element is positioned in said slot with the eye of the eye bolt or the loop of the terminal element in alignment with the cylindrical portion of the angle plate, a headed 100 pin 28 is placed within the cylindrical portion of the angle plate from above with its intermediate portion engaging such eye or loop. Prior to thus engaging the fastening device with the angle plate said angle plate should be securely mounted against the inner faces of the corner post 1 and side frame member 2 of the article of furniture by driving screws 29 through screw holes of the flanges of said angle plate into the inner 105 portions of the side frame members.

The corner bracing device shown in Figs. 5, 7 and 8, is particularly adapted for use with a swinging corner bolt of the type just described. The brace portion of said corner bracing device comprises a plate 31 preferably formed of sheet metal having a flat body portion and a plurality of projecting teeth 32 in spaced relation to each other at 110 each end of said body portion. Said teeth 115

are preferably angularly disposed with respect to the body portion of the plate so that the teeth may be substantially at right angles to the inside surfaces of the side members of the article of furniture into which they are intended to be pressed. Centrally of the body portion of the brace plate an elongated slot 33 is formed, said slot being adapted to fit over the shank of the corner bolt. Adjacent the bottom edge of the body portion of the brace plate a pair of ears 34 are provided. Said ears are preferably struck up rearwardly from the body portion of the plate in spaced relation to the end portions thereof and, as shown in Fig. 5, serve to act as guides against the lateral displacement of the top plate of the bracing device.

The top plate of the bracing device, as clearly shown in Fig. 8, comprises a curved body portion 41 having an integral hook 42 formed at right angles thereto at its lower end and having a pair of inwardly turned integral flanges 43, 44, at said upper edge. Said flanges are preferably spaced from each other by means of a V-shaped slot 44 and each of the same has a flat bearing edge 43, 46, adapted to rest against the outer surface of the brace plate. At a point along the central line of the body portion of the top plate, slightly above the center thereof, a hole 47 is provided through which the shank of the clamping bolt is passed after the brace plate has first been positioned thereover. A washer 48 and nut 49 are then secured to the screw threaded end of the corner bolt and the nut is turned until the teeth of the brace plate are engaged with the side frame members.

After a bracing device of either of the types heretofore described has been placed in each corner of an article of furniture, as shown in Fig. 1, the terminal portions 6 of the flexible members of the tensioning device are engaged over the hooks formed at the lower ends of each of the corner plates. The turn-buckle is then manipulated so as to apply tension through the flexible members to the corner portions of the article of furniture until a sufficient distance has been attained to give said article the necessary degree of rigidity.

It is obvious that when an angle plate of the character shown in Fig. 6 is used on an article of furniture, such as a davenport or an elongated table, that the corner bolt, or the terminal element of the flexible member, in the event direct connection is made, will result in angular adjustment of said device about the supporting pin 28 positioned within the cylindrical portion of the angle plate. The elongated slots formed in the corner plates, shown in Figs. 2 and 4, and the brace plate, shown in Fig. 7, readily permits lateral movement of the eye bolt 27 when

the same must be swung to one side when applied to a piece of furniture having an elongated frame. The ears 34 shown on the brace plate are spaced a sufficient distance to permit adequate lateral movement 70 of the top plate 41 when that type of corner brace is employed.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a furniture construction, the combination of a plurality of corner posts, main side frame members interposed between said posts, a plurality of lever members secured 85 adjacent the central plane of said side members to said respective corner posts, and means for applying tension to one end of each of said lever members and moving its opposite end diagonally toward the adjacent 90 side members.

2. In a furniture construction, the combination of a plurality of corner posts, main side frame members interposed between said posts, a bolt secured in diagonal relation to 95 each post, a corner bracing device adjacent the inner side of each post adapted to be engaged over the adjacent bolt, a bearing member formed at the upper end of each bracing device, and means associated with the lower 100 ends of the respective bracing devices for moving said ends inwardly.

3. In a furniture construction, the combination of a plurality of corner posts, main side frame members interposed between said 105 posts, a bolt secured in diagonal relation to each post, a corner bracing device adjacent the inner side of each post having a transverse slot adapted to be engaged over the adjacent bolt, a bearing member formed at 110 the upper end of each bracing device, and means associated with the lower ends of the respective bracing devices for moving said ends inwardly.

4. A furniture brace comprising a series 115 of fixtures secured diagonally to the corners of an article of furniture and in pressure applying relation to the side members thereof, a corner bolt for each of said fixtures securing the same to the corner posts, a central tensioning device, and means connecting said corner fixtures at points spaced from said bolts with said tensioning device in pressure applying relation thereto.

5. A furniture brace comprising a series 120 of plates secured diagonally to the corners of an article of furniture and in pressure applying relation to the side members thereof, a corner bolt for each of said plates securing the same to the corner posts, a central ten-

sioning device, and means connecting said corner plates at points spaced from said bolts with said tensioning device in pressure applying relation thereto.

5. 6. A corner plate for a furniture brace comprising a body portion having downwardly inclined sides, a terminal section at the lower end extending inwardly at right angles thereto and provided with means for
10 attaching a flexible member, the upper end of said body portion having lateral extensions with bearing members at the ends thereof.

7. An angle plate for a furniture brace

comprising a cylindrical central portion 15 adapted to receive a locking bolt, intermediate extension plates continuous with said cylindrical central portion and angularly related to each other, said plates and central portion being provided with a transverse 20 slot to receive the loop of a fastening device, and extension flanges connected with said intermediate plates for securing said device to the side frame members of an article of furniture.

Signed by me, this 18th day of October, 1924.

THEODORE H. WITTLIFF.
